UNITED STATES PATENT OFFICE.

ERWIN EHRHARDT, OF WAIDMANNSLUST, NEAR BERLIN, GERMANY, ASSIGNOR TO SIEMENS & HALSKE A.-G., OF SIEMENSSTADT, NEAR BERLIN, GERMANY, A CORPORATION OF GERMANY.

ELECTRICAL SIGNALING SYSTEM.

1,197,273.

Specification of Letters Patent. Patented Sept. 5, 1916.

Application filed August 4, 1914. Serial No. 854,991.

To all whom it may concern:

Be it known that I, ERWIN EHRHARDT, German citizen, and resident of Waidmannslust, near Berlin, Germany, have invented certain new and useful Improvements in Electrical Signaling Systems, of which the following is a specification.

This invention relates to an electrical signaling preferably telephone system comprising an apparatus for electrically controlling certain operations from a distance by means of oscillatory elements, such as a gravity pendulum or a spring controlled oscillatory member which are provided at the receiving station and at the sending station and which swing in synchronism with each other for influencing contact elements which effect said operations.

In practice the synchronism of two freely swinging oscillating elements cannot be maintained with absolute accuracy, for after a certain number of oscillations a discrepancy in the swinging of the two elements will be inevitable. The reason for this is partly due to the fact that the frictional resistance in the several devices is different and varying with the time and partly because it is not possible to attain absolutely identical masses or lengths of the oscillatory members or the same tension of the springs for driving the same and so forth.

According to this invention the aforementioned disadvantage is avoided in employing apparatus for preventing an injurious adding up of the small discrepancies which occur during each oscillation of the systems. This is done by automatically locking the oscillatory members after a certain short time, so that the diversities of oscillation which have taken place in the meanwhile will not exert an injurious influence on the operation to be controlled at a distance. After the systems have thus been locked the same are again released simultaneously, so that the process of oscillation will repeat itself. This locking and releasing of the oscillatory members is carried on in periodical alternation, so that these members will practically swing in absolute synchronism. It will be advantageous to lock the members as early as after a half or a full oscil-

lation, so that the difference in the motions of the two members will be so small as to be practically without any effect. Such oscillating members comprise chiefly two types, one, synchronously oscillating gravity pendulums and the other type, oscillating disks controlled by a spring. The gravity pendulum type has the disadvantage that in order to ascertain a quick transmission of signal impulses, very short pendulums must be used with which it is difficult to obtain a sweep long enough to place a sufficient number of contacts. In order to do this it would be necessary to provide these pendulums with heavy masses in order to make up for the frictional losses which are considerable on wiping contacts and which materially affect the synchronous operation of the pendulum members. Therefore in practice, the use of gravity pendulums has limits far below the bounds of exactness which must be required for arrangements for transmitting signals or the like. To overcome these disadvantages I employ according to the present invention, oscillatory members, which are operated by spring power; for instance strong springs may be employed and the momentum of inertia of the swinging masses rendered small so that a greater number of oscillations is obtained. Also in spring-operated oscillatory members the frictional resistances can be made to exert only a small influence. Furthermore with oscillatory members operated by spring-power the motion of the contact making parts can take place in the same direction in contradistinction to the oscillating motion of the gravity pendulum, and the contacts may be made strong.

The invention may be employed in various ways for long distance transmission of signals. For instance, it may be employed in telegraphic type-printing or kindred apparatus for closing lamp contacts or giving other signals at a distance.

In the accompanying drawings I have shown an application of my invention to a system for making signals through lamps. In these drawings, Fig. 1 shows two oscillating systems operated by spring power, and the connections between the systems, Fig. 2 shows a detailed full view of

the oscillating member at the receiving station, Fig. 3 shows a side view and Fig. 4 shows a plan view of the member shown in Fig. 2, illustrating several constructional details.

In Fig. 1 the spring-operated oscillatory devices of the sending station and the receiving station are provided with a casing 43 which is mounted in bearings 40 and 41 upon the axle W, as shown in Fig. 2, so that said casing is rotatable around the latter. A spiral spring 44 is arranged in the interior of said casing, one of the ends of said spring being connected to the axle W and the other 10 of its ends being fixed at the casing, as shown in Fig. 3. A locking detent 45 is provided at the axle, which detent retains in a certain position the axle W by means of locking levers 46 and 47. In this position the 15 spiral spring 44 is kept under tension by an advance of the spring casing 43 which amounts to little more than a half-revolution, in which position this casing is held by a coupling pin 48, as shown in Fig. 2, the 20 purpose of which is more fully explained below. If thereupon an electro-magnet 50 controlling the locking lever 47 is excited by a short current impulse, the lever 47 will 25 release the locking detent 45 and the spring 30 44 is permitted to transmit rotation to the axle W in the direction shown by the arrow.

The axle W carries a fly-wheel 51, as shown in Fig. 2, which stores up the energy given off by the spiral spring 44 and transmits the same again to the axle W and the spring as soon as the latter has come into condition of no-tension. The axle accordingly will be rotated further and the spring 44 will be brought from its condition of no-tension into condition of tension which with respect to direction is opposite to that in said first position. The fly-wheel and the tension of the spring are so proportioned that the axle W is just able to make one revolution and that at the end of said revolution the locking at the detent 45 by the levers 46 and 47 will again take place in an automatic manner.

During the rotation of the axle a contact 50 arm 52, as shown in Figs. 1 and 2, which is mounted upon the axle W slides over the segments of a contact disk 53 for giving off and receiving the impulses of a signaling current passing through the transmission line L₁, L₂ as more fully explained below.

In order to restore the original condition of the spring 44 after each revolution of the axle W, so that at each releasing the same procedure will repeat itself and more particularly in the same direction of motion, a device is employed which permits the spring casing 43 to be rotated to follow the spring for again winding up the same. This device consists of a second axle W', as shown 60 in Fig. 2, which is mounted in bearings 55

56 in line with said first axle W. The axle W' also carries a spring casing 57 which is mounted so that it can loosely rotate thereon, but so that it is undisplaceable in longitudinal direction. The casing 57 carries in its 70 interior a spiral spring 54 whose inner end is fixed at the axle W' and whose outer end is fixed at the casing. A conical gear 58 is further connected to said casing which gear meshes with a second conical gear 59, mounted upon the axle of a motor 60, as shown in Fig. 4. The motor is controlled by a frictional locking device 62 acting upon a disk 61, so that said motor is prevented from rotating in backward direction, thus causing 80 the axle W' to be permanently under the influence of the spring 54. The circuit for the motor leads over the contacts 63, 64 which ordinarily are open, and which are closed as soon as the tension of the spring 85 decreases by a certain amount, so that the motor is caused to rotate, thereby again causing the spring to be wound up. For this purpose a lever 65 carrying a contact 63 is provided in the path of motion of a sleeve 90 66 which is splined to axle W' so that it is undisplaceable in axial direction but not rotatable thereon. This sleeve carries an outer thread with which the inner thread of the spring casing 57 meshes. As the casing is 95 undisplaceable upon the axle W' in axial direction, the sleeve 66 during rotation of the casing displaces itself in axial direction in such a manner that at a definite amount of release of the spring power of the spring 100 the sleeve 66 moves the lever 65 and closes the circuit for the motor. Associated with the axle W' is furthermore a locking device 70, 71, 72, as shown in Fig. 1, which essentially corresponds to the locking device, 105 70, 71, 72, which has above been described for controlling the axle W. A fly-wheel 73 is also provided, as shown in Fig. 2, which carries a pin 48. This pin together with a projection 74 at the spring casing 43 of the first 110 axle W represents a rigid coupling between the axle W' and the spring casing 43.

The common operation of the two axles and springs is as follows:—If the axle W is released by the lever 47 the detent 45 115 presses for one instant the lever 46 downward before it is locked by the same during the end of the operation. This lever thereby temporarily closes a contact 75, 76 therewith causing a current impulse over the locking magnet 77 of the second axle W'. This axle is thereby also released and makes one revolution whereby by means of the coupling 73, 48, 74, 43 it gives an opportunity to this spring 44 of the first axle W to 120 release its spring power and to be again wound up by the energy of the fly-wheel 73 on the second axle W'. In this case the spring 54 of the axle W' does act to impart tension to the spring 44 to such an extent as 130

this latter has lost its power by overcoming frictional or other resistances. In this manner in every case it is attained that the full original position is reached. The additional energy which is given off by the second spring is from time to time supplied by the motor 60.

- The electrical operation taking place during the signaling can be seen from Fig. 1.
- 10 At the sending station there are again three keys T_1 , T_2 , T_3 to which the relays R_1 , R_2 , R_3 correspond at the receiving station. If, for instance the key T_2 be pressed downward, a contact 80 is closed which is at first 15 without any effect. As soon as, however, the neighboring contact 81 is closed by the key, a current flows from the battery 78 over a sliding brush 82, the brush arm 52, segment O of the disk, contact 81, through the body 20 of the key and through the winding of a relay R. This relay possesses two armatures 83, 84 which are attracted simultaneously upon excitation of the same, therewith closing contacts 85 and 86. By making contact at 85 a condenser 79 is charged from a battery 67 over the releasing magnet 50 of the axle W and therewith this axle is released. At the same time by making contact at 86 a current flows from a battery 68 over the transmission L_1 , L_2 and a relay RE of the receiving station E. This relay closes the contact 87 whereby a current is caused to flow from a battery 68 over the contact arm 52 of the receiver, the segment 30 O thereof, a condenser 88 and the releasing magnet 37_a of the axle W at the receiver. In this case also the axle W is rendered free and both contact arms 52 of the oscillatory member of the sending and receiving station 40 will now synchronously contact over the segments of the contacting disk 53. At the end of the revolution of the contact arms 52 and the sending and receiving station, as above pointed out, the releasing magnet 77 is excited and therewith the axle W is set 45 in rotation thus causing the springs to be again wound up for the subsequent transmission of a signal. In order to be able to employ the discharge current of the condensers 79 and 86 for each new revolution of the contact arms 52 and the excitation of the releasing magnets 50 and 37_a, said condensers are bridged by high resistances 49 over which they gradually discharge during 55 the revolution of the contact arms. Connected with the segments 1', 2', 3' of the receiver disk 53 are the relays R_1 , R_2 , R_3 , the working contacts 89 of the latter being connected to the incandescent lamp 19, 20. As 60 the key T_2 at the sending station is pressed downward during the contacting process of the segment 2' at the sending station, a second current impulse is given by battery 78 to relay R, which causes a second impulse to 65 be sent over the transmission line L_1 and L_2 .

by means of contacts 85, 86 as described before which current impulse connects the armature of the relay R_2 with its working contact by the aid of the relay RE and the segment 2', said armature being then locked 70 from underneath by a pawl 90. In this manner the circuit for feeding the lamp may thereby be immediately switched into circuit; for many purposes, however, especially in case of combination-signals, it is advantageous to cause the signal to come into effect not before the accomplished adjustment of all relays R_1 — R_3 which come at a time into action. For this purpose the second axle 75 W' of the receiver E carries a contacting device consisting of an insulating disk 91 having a metal segment 92 inserted therein which contact device is switched into circuit together with the incandescent lamps 19, 20, thus causing the signal prepared at the 80 relay contacts to be released subsequent to the rotation of the axle W'. The disk 91, 92 for closing the current further serves to counteract the locking of the armatures of the relays R_1 — R_3 . For this purpose an electro-magnet 93 is provided which also is excited after the complete rotation of the axle W' and which attracts a rail 94 bringing the catches or pawls 90 temporarily out of engagement with the armature of the relay 95 therewith releasing the same. The magnet 93 works with considerable retardation, so that the transmitted lamp signal remains for a certain length of time.

Having thus described my invention, what 100 I claim is:

1. In a system for electric transmission of signals, the combination of a contact system at the sending and a contact system at the receiving station, an oscillatory member associated with each of said contact systems for operating the same in synchronism, releasing means permitting a simultaneous release of said oscillatory members from the sending station, locking means for locking 105 said members after a predetermined time of swinging, and springs for periodically operating said members, the force of said springs and the mass of said members being properly dimensioned to overcome the effect 110 of the friction for attaining a desired duration of swinging.

2. In a system for electric transmission of signals, the combination of a contact system at the sending and a contact system at the receiving station, an oscillatory member associated with each of said contact systems for operating the same in synchronism, releasing means permitting a simultaneous release of said oscillatory members from the 120 sending station, locking means for locking said members after a predetermined time of swinging, and springs for operating said members, the power of said springs and the masses of said members being so dimen- 125 130

sioned that said members will swing in a full or approximately full revolution.

3. In a system for electric transmission of signals, the combination of a contact system at the sending and a contact system at the receiving station, an oscillatory member associated with each of said contact systems for operating the same in synchronism, releasing means permitting a simultaneous release of said oscillatory members from the sending station, locking means for locking said members after a predetermined time of swinging, springs for operating said members, the power of said springs and the masses of said members being so dimensioned that said members will swing in a full or approximately full revolution, and means for periodically imparting a tension to said springs in uni-directional sense after each oscillation of said members, whereby uni-directional motion will be periodically imparted thereto.

4. In a system for electric transmission of signals, the combination of a contact system at the sending and a contact system at the receiving station, an oscillatory member associated with each of said contact systems for operating the same in synchronism, releasing means permitting a simultaneous release of said oscillatory members from the sending station, locking means for locking said members after a predetermined time of swinging, springs for operating said members, the power of said springs and the masses of said members being so dimensioned that said members will swing in a full or approximately full revolution, means for periodically imparting a tension to said springs in uni-directional sense after each oscillation of said members, whereby uni-directional motion will be periodically imparted thereto, said latter means consisting of an axle for changing the direction of the tension of said springs, and coupling means inserted between said springs and said axle.

5. In a system for electric transmission of signals, the combination of a contact system at the sending and a contact system at the receiving station, an oscillatory member associated with each of said contact systems for operating the same in synchronism, releasing means permitting a simultaneous release of said oscillatory members from the sending station, locking means for locking said members after a predetermined time of swinging, springs for operating said members in a full or approximately full revolution, means for periodically imparting a tension to said springs in uni-directional sense after each oscillation of said members, said latter means consisting of an axle for changing the direction of the tension of said springs, coupling means inserted between said springs and said axle, said axle being further adapted to simultaneously

convey to said members an amount of energy which had been previously lost by friction.

6. In a system for electric transmission of signals, the combination of a contact system at the sending and a contact system at the receiving station, an oscillatory member associated with each of said contact systems for operating the same in synchronism, releasing means permitting a simultaneous release of said oscillatory members from the sending station, locking means for locking said members after a predetermined time of swinging, springs for operating said members in a full or approximately full revolution, means for periodically imparting a tension to said springs in uni-directional sense after each oscillation of said members, said latter means consisting of an axle for changing the direction of the tension of said springs, coupling means inserted between said springs and said axle, said axle being constructed to make at the same time contacts for the simultaneous reproduction of the signals received during the swinging of said members.

7. In a system for electric transmission of signals, the combination of a contact system at the sending and a contact system at the receiving station, an oscillatory member associated with each of said contact systems for operating the same in synchronism, releasing means permitting a simultaneous release of said oscillatory members from the sending station, locking means for locking said members after a predetermined time of swinging, springs for operating said members in a full or approximately full revolution, means for periodically imparting a tension to said springs in uni-directional sense after each oscillation of said members, said latter means consisting of an axle for changing the direction of the tension of said springs, coupling means inserted between said springs and said axle, said axle being constructed as freely movable fly-wheel body and adapted to receive its motion from said springs, and a separate source of power for imparting an additional force to said springs.

8. In a system for electric transmission of signals, the combination of a contact system at the sending and a contact system at the receiving station, an oscillatory member, associated with each of said contact systems for operating the same in synchronism, releasing means permitting a simultaneous release of said oscillatory members from the sending station, locking means for locking said members after a predetermined time of swinging, springs for operating said members in a full or approximately full revolution, means for periodically imparting a tension to said springs in uni-directional sense after each oscillation of said members, said latter means consisting of an axle for

changing the direction of the tension of said springs, coupling means inserted between said springs and said axle, and motor means for periodically imparting a moving force to said axle after the tension of said springs has attained a minimum value.
